UNITED STATES PATENT OFFICE.

CLAYTON CHESTER FERGUSON, OF JERSEY CITY, NEW JERSEY.

ELECTRIC SWITCH.

Application filed November 7, 1925. Serial No. 67,578.

This invention relates to an electric switch.

The object of the invention is the production of a switch, which is operated by a detachable key. The second object of the invention is the production of an electric switch, which is operated by manipulating the key thereof in a predetermined way. The third object of the invention is the production of a switch, with a key which will enter the switch when not properly inserted and when turned will fail to function with the switch, and which cannot be removed unless in proper position. The fourth object of the invention is the production of a switch with a key, which when turned or operated by a user not conversant with the device invites the incorrect insertion of the key, and thereby avoids the functioning of the switch when the key is turned. The fifth object of the invention comprises an electric switch with a key, that requires to be moved to a predetermined position for its withdrawal. The sixth object of the invention is the production of a switch which is of very simple construction, and which can easily be attached in place to the panel of a radio apparatus and the like, and for other objects.

In the accompanying drawing Fig. 1 represents a partial enlarged side view and partial section of the switch with its key as on the line 1, 1 of Fig. 2; Fig. 2 indicates a left hand side view of Fig. 1; Fig. 3 shows a top plan view of Fig. 1; Fig. 4 shows a section of Fig. 1 on the line 4, 4; Fig. 5 indicates a left hand view of Fig. 1 with an element removed; Fig. 6 shows a left hand view of Fig. 1 with some of its elements in a changed position; Fig. 7 indicates an enlarged side elevation of the key of the switch and Fig. 8 represents a section of Fig. 7 on the line 8, 8.

The switch is indicated with the foundation block 20 of electric insulating material, which is threaded for the threaded bushing 21, having the head 22 with the slots 23. A cylindrical opening 24 is formed in said bushing 21, and it clamps the block 20 in place to the panel 26. Clamping screws and binding posts 30 and 31 are indicated in threaded engagement with the foundation block 20. Pins 32 and 33 extend up from the foundation block 20. A cover plate of electric insulating material indicated at 35 is located above the said foundation block 20, and is provided with a pair of openings in

which are tightly fitted the metallic sleeve 36 with the shoulders 37, and the metallic sleeve 38 with the shoulder 39 at one end. The screw 30 extends through the sleeve 36 and the screw 31 extends through the sleeve 38.

A flexible switch locking member is indicated in its entirety by the numeral 40. The said member comprises the practically circular portion 41, which encircles the screw 30, and then bends around the pin 32 as indicated at 42. A bow 43 extends from the bend 42 and from the latter extends the contact arm 45, with a portion thereof normally bearing against the pin 33 as indicated in Fig. 5, when the key to be described is not inserted in the switch. In this position the contact arm 45 is positioned to the left hand side of the axial opening of the bushing 21, dividing it into the small segment 46 and the large segment 47.

A terminal wire 48 for electric current has one end clamped between the head of the screw 30 and the sleeve 36, and a second terminal wire 49 has one end clamped between the head of the screw 31 and the sleeve 38.

The switch key is indicated with the cylindrical shank 50, to one end of which is fastened the operating knob 51. The latter may have an indicator thereon, as shown by the knurled portion 52, to guide the user in turning the key to its proper position. At the other end of the shank 50 is formed a truncated portion 53 with the apex 54 at the cylindrical surface of said shank. An annular groove 55 is formed between the said truncated portion 53 and the main portion of said shank. A deep flat recess 56 is formed with said groove 55 at one portion thereof. A ramp 57 spirally extends from the annular groove 55 to the cylindrical surface of the shank between said deep recess 56 and the truncated portion 53.

Before the insertion of the key into the switch the contact arm 45 is normally located in its non-operative position to the left of the axial center of the bushing 21, dividing the cylindrical opening thereof into the small segment 46 and the large segment 47 as indicated in Fig. 5.

The user to operate the switch inserts the shank 50 of the key through the opening of the bushing 21 with its apex 54 extending through the small segment 46. Thereby the said contact arm 45 is located and seated in the deep recess 56 of the key as indicated

in Fig. 4. The key is now turned to cause the cylindrical wall of the groove 55 to bear against the arm 45, which forces said arm in contact with the sleeve 38 as best shown in Fig. 6 and thereby the electric circuit of the switch is closed.

If the operator inserts the apex 54 of the truncated portion 53 in and through the large segment 47 and turns the key, it will only further separate the arm 45 from the sleeve 38, and the switch will not function. The key in either case is engaged by the groove 55 or recess 56, and cannot be removed from either unless turned in proper position. If the key is turned to seat the arm 45 into the recess 56 the switch locking member 40 is spaced from the binding post 31 and the electric circuit through the switch is broken.

To withdraw the key from the switch, the operator turns it until the arm 45 bears on the cylindrical wall of the groove 55, and then farther turns the key and pulls it until said arm 45 rides on the ramp 57, until it reaches the outer cylindrical surface of the shank of the key, adjacent to the truncated portion 53, when said key can be released from the switch.

Various modifications may be made in the invention, and the present exemplification is to be taken as illustrative and not limitative thereof.

Having described my invention what I desire to secure by Letters Patent and claim is:

1. In an electric switch the combination of a foundation block, a bushing extending through the block, a pair of binding posts for wires to conduct electric current extending from the block, a flexible switch locking member having a contact arm, one end of said member clamped to the foundation block by means of one of said binding posts, the contact arm of said member normally extending over the opening in said bushing, a key with its shank adapted to be inserted through said bushing to swing said switch locking member, said shank having a groove to seat said contact arm in proper position to locate said member in contact with the second binding post to close the electric circuit of the switch, and a deep recess in said shank to seat said contact arm in position to space the switch locking member from said second binding post to open the electric circuit of the switch.

2. In an electric switch the combination of a foundation block, a bushing with an opening extending through the block, a pair of binding posts for wires to conduct electric current extending from the said block, a flexible switch locking member having a contact arm, one end of said member clamped to the foundation block by means of one of said binding posts, the contact arm of said member normally extending

over the opening in said bushing and dividing the cross area thereof into a small segment and a large segment, a key with its shank adapted to be inserted in the opening of said bushing either through its small segment or large segment, said shank having a groove to swing said contact arm in proper position, to locate said member in contact with the second binding post to close the electric circuit of the switch when said shank is inserted into the bushing through its small segment, and to space it from said second binding post, when inserted through said large segment, said shank having a deep recess formed therein to seat said contact arm and thereby space said locking switch member from said second binding post, to break the circuit of the switch, both said groove and recess functioning to lock the key to the switch and means incorporated in said shank to unlock the key from the switch.

3. In an electric switch the combination of a foundation block, a bushing with a cylindrical opening extending through the said block, a pair of binding posts for wires to conduct electric current extending from said block, a flexible switch locking member having a contact arm, one end of said member clamped to the foundation block by means of one of said binding posts, the contact arm of said member normally extending over the opening in said bushing and dividing the cross area thereof into a small segment and a large segment, when the key for the switch is not inserted therein, a key with a cylindrical shank for the switch, adapted to be inserted through said bushing, said shank having a truncated end with an apex at its cylindrical wall, an annular groove formed in the shank below its truncated end, a deep recess associated with said annular groove and a ramp extending toward said truncated end from said groove to the cylindrical portion of the shank.

4. In an electric switch the combination of a foundation block having an opening, a pair of binding posts for wires to conduct electric current connected to the block, a switch locking member having one end thereof connected to one of said binding posts, the free end of said member normally extending across the opening in said block, a key having a shank adapted to be inserted in said opening to swing said switch locking member, said shank having a groove to seat said member in proper position to locate it in contact with the second binding post to close the electric circuit of the switch, and a deep recess in said shank to seat said member in position to space it from the second binding post to open the electric circuit of the switch.

5. In an electric switch the combination of a foundation block with an opening therethrough, a pair of binding posts for wires

to conduct electric current, a switch member with a portion thereof in connection with one of said binding posts, and its free end normally across said hole dividing its area 5 into a pair of supplementary openings, a key adapted to be inserted through the opening in said foundation block and to enter either of said supplementary openings, said key adapted to move said switch member 10 in one direction when inserted in one of

said supplementary openings and in the opposite direction when inserted in the other supplementary opening, the key when inserted in one of said supplementary openings closing the electric circuit of the switch 15 and when inserted in the other supplementary opening maintaining the circuit open.

In testimony whereof I affix my signature.

CLAYTON CHESTER FERGUSON.
